HIS ATTORNEY.

UNITED STATES PATENT OFFICE.

CHARLES L. JOHNSON, OF SAN JOSE, CALIFORNIA.

DEVICE FOR TEETHING INFANTS.

1,268,470.

Specification of Letters Patent. Patented June 4, 1918.

Application filed January 28, 1918. Serial No. 214,200.

To all whom it may concern:

Be it known that I, CHARLES L. JOHNSON, a citizen of the United States, residing at San Jose, in the county of Santa Clara and 5 State of California, have invented a new and useful Improvement in a Device for Teething Infants, of which the following is a specification.

This invention relates to improvement in 10 a device for teething infants and its objects are—

First: to so provide and construct a device for teething infants, of pliable rubber, adaptable to the infant's mouth and one that 15 the infant cannot swallow.

Second: to so construct a pliable rubber device that, regardless of how the infant takes hold of the device, there is always an end for him to bite on.

20 Third: to so construct a device for teething infants that will have a plurality of projections for the infant to bite on, and one that will not readily roll out of the infant's reach.

25 A still further object of my invention is generally to improve this class of devices, so as to increase their utility, durability and efficiency.

With these and other objects in view, my 30 invention will be more fully described and illustrated in the accompanying drawings, and then more specifically pointed out in the claim which is attached to and forms a part of this application.

35 In the drawings:

Figure 1 is a perspective view of my device for teething infants.

Fig. 2 is a plan view of my device for teething infants.

40 Corresponding and like parts are referred to in the following description and indicated in all the views of drawings by the same reference numerals.

45 My improved device for teething infants, forming the subject matter of the present

invention comprises a device made of pliable rubber, having a plurality of projections 1, adapted to enter the infant's mouth and to be grasped by the infant's hands; the projections 1 are integral, one with the other 50 by being cast or produced from a solid piece of rubber of the required resiliency, and are of a size and length suitable. The outer ends of these projections 1 are convex in shape as at 2.

55 The operation of my device is as follows—

The infant grasps the device and inserts any one of the projections in its mouth to bite or chew on, the other projections preventing the device from entering the mouth 60 too far, said projections being easily grasped by the infant's hands.

65 The plurality of projections being so arranged, the device will not easily roll out of the infant's reach.

Having thus described my invention, what I claim as new and desire to secure by Letters Patent is—

A device of the character described, made of pliable rubber of the required resiliency, 70 consisting of a plurality of projections, cylindrical in shape, the outer ends of which are convex in contour; the inner ends of these projections being integral, one with the other; each projection being diametrically opposite another projection, and all projections extending from a common center, in a plurality of planes, as the radii of a sphere, any one of these projections being adapted to enter the infant's mouth or to be 75 grasped by the infant's hands, as and for the purpose described.

In testimony whereof I have hereunto set my hand in presence of two subscribing witnesses.

CHARLES L. JOHNSON.
